UNITED STATES PATENT OFFICE.

CORA A. BUTLER, OF CHICAGO, ILLINOIS.

BURNER AND SUPPORT FOR VAPORIZERS.

960,500.

Specification of Letters Patent. Patented June 7, 1910.

Application filed March 3, 1909. Serial No. 481,064.

To all whom it may concern:

Be it known that I, CORA A. BUTLER, a citizen of the United States, residing at Chicago, in the county of Cook and State 5 of Illinois, have invented certain new and useful Improvements in Burners and Supports for Vaporizers, of which the following is a specification.

In the drawings, Figure 1 is a perspective view, showing the burner, stand and vaporizer assembled; Fig. 2 a plan view of the burner and stand; and Fig. 3 a side elevation of the device shown in Fig. 2.

This invention relates more particularly 15 to that form of vaporizers which is used in combination with a screen or cabinet for steaming the face with a medicated compound; and has for its object to form with the burner, for heating water in the vaporizer, a stand for holding the receptacle into 20 which the water is placed and a stand for supporting the vaporizer, the legs of the stand being formed to give the stand firm support.

25 Further objects will appear from a detailed description of the invention, which consists in the features of construction and combination of parts hereinafter described and claimed.

30 A receptacle or tank 4, in which water is placed, is connected by a pipe 5 to a small receptacle 6, in which is placed some form of medicated preparation. Extending from the receptacle 6 is a nozzle 7, out of which 35 the steam passes, and attached to the pipe connecting the nozzle to the receptacle is an upright support 8 having a hood 9 which encircles the user; but as all of these elements are old and covered in a former patent 40 issued to me August 4, 1903, No. 735,461, it is not considered necessary to describe in detail their construction and operation.

The receptacle 4 has surrounding its body a bead 10 adapted to be entered into notches 45 11 cut in the face of arms 12 upwardly extending from a plate 13, which plate constitutes the upper portion of the burner. The notches 11, upon all but one of the arms, 50 are beveled upon their side faces, so that when the bead on the receptacle is placed therein it will be wedged into the notch and held securely. The notch in the remaining arm, is of a right angle formation and is adapted to have entered through its side 55 wall a thumb screw 14, the end of which will bear against the bead 10 on the recep-

tacle 4, which arrangement permits of the easy positioning of the receptacle, but allows no movement after being positioned. The arms 12 are cast integrally with the 60 plate 13, which plate forms that part of the burner which spreads the flame in proper manner around the base of the receptacle. The plate 13 is joined, by means of a bolt or otherwise, to a casting 15, which has formed in its upper portion a chamber 16, in which the combustion of the gas takes place, the chamber and plate constituting a burner 17. The chamber has formed therewith and extending downwardly therefrom 65 legs 18 forming a base or support for the vaporizer, the legs being of somewhat greater span than ordinary so as to prevent easy upsetting of the vaporizer. This is of 70 extraordinary importance in a device of 75 this nature, because of the fact that the head of the user is covered, and in case of the upsetting of the stove a serious catastrophe might result. A gas induction pipe 19 enters into the chamber 15 and is provided with an 80 air duct 20 formed by cutting away a portion of the pipe.

It will thus be seen that the two sections constituting the burner each have arms formed integrally therewith,—the arms 85 formed with the lower section of the burner constituting a support for the entire device, and the arms formed with the upper section constituting a support for the receptacle or tank of the vaporizer, thus combining, in 90 the ordinary castings which constitute the burner, a supporting means for the vaporizer as a whole, and a supporting means for the receptacle or tank of the vaporizer. This materially reduces the cost of construction 95 of the apparatus and makes a more substantial rest than that afforded by the ordinary construction of burner, and at the same time the construction is one which is symmetrical and does not in any way detract from the 100 general appearance of the apparatus.

What I regard as new and desire to secure by Letters Patent is:

1. In combination with a vaporizer having a laterally extending pipe adapted to support a hood, a heater provided with a plurality of widely distended legs, and a plurality of arms adapted to receive and clamp the vaporizer in position to sustain the hood, substantially as described. 105

2. In combination with a vaporizer having a laterally extending pipe adapted to 110

support a hood, a heater provided with a plurality of widely distended legs, a plurality of arms adapted to receive and clamp the vaporizer in position to sustain the hood, 5 and a thumb screw entered through one of the arms and adapted to bear against the vaporizer to clamp the same in position, substantially as described.

3. In combination with a vaporizer comprising a tank or receptacle and a laterally extending pipe rigidly secured thereto and adapted to support a hood, a heater provided with a plurality of widely distended

legs, a plurality of arms adapted to receive and clamp the vaporizer in position to sustain the hood, each of the arms being notched at its upper end to engage the sides of the vaporizer tank or receptacle, and a thumb screw entered through one of the notched arms and adapted to bear against the tank 15 or receptacle to clamp the same in position, substantially as described.

CORA A. BUTLER.
